UNITED STATES PATENT OFFICE.

JOHN W. BROWN, OF CLEVELAND, OHIO, ASSIGNOR TO NATIONAL CARBON COMPANY, OF CLEVELAND, OHIO, A CORPORATION OF NEW JERSEY.

BATTERY-CELL.

No. 838,165.

Specification of Letters Patent.

Patented Dec. 11, 1906.

Application filed June 4, 1906. Serial No. 320,047.

To all whom it may concern:

Be it known that I, JOHN W. BROWN, a citizen of the United States, residing at Cleveland, in the county of Cuyahoga and State of Ohio, have invented a certain new and useful Improvement in Battery-Cells, of which the following is a full, clear, and exact description.

The object of this invention is to produce a battery-cell which may be kept for a long time without deterioration, but which may be very quickly and easily made ready for immediate use.

The invention is more particularly an improvement upon the ordinary dry cells in general use, and is so shown in the drawings. The ordinary dry cell comprises a zinc cup lined with bibulous material, a carbon electrode centrally placed in the cup, and a filling 20 of moist granular material, whose compositions and function are well understood by those familiar with this art. The cell is completed by a seal of pitch or some analogous material placed in the top of the cup around the carbon electrode. Such dry cells begin to deteriorate immediately they are completed, even though not put to use, and after 25 a time become substantially useless for practical purposes.

The present invention has for its primary purpose the production of a battery-cell which as constructed will not deteriorate, but may be very easily transformed, so as to be immediately useful and effective.

The invention may be summarized as consisting of the combinations of parts herein-after described, and pointed out definitely in the claims.

In the drawings, which show the best and 40 most practical form of the invention now known to me, Figure 1 is an elevation, partly broken away, of a dry cell embodying the invention, showing the form in which the cell is constructed for sale. Fig. 2 is a plan view thereof, partly broken away. Fig. 3 is an elevation of the cell when transformed for use, the drawing showing the outer casing partly broken away. Fig. 4 is an elevation, partly broken away, of the inner zinc cup of 45 the cell. Fig. 5 is an elevation, partly broken away, of the package which contains all of

the battery parts and constituents except the metallic cups. The wrappings of this package are partly broken away to show its construction. Fig. 6 is a bottom plan view of 55 the cup shown in Fig. 4, and Fig. 7 is a sectional view on line 7-7 of Fig. 5.

The battery includes a cup A, which is expansible in diameter and is preferably made of zinc, so as to serve as the positive electrode. 60 It is preferably not exactly cylindrical, but, on the contrary, is tapered slightly, so as to be a little larger in diameter at the top than at the bottom. It may be formed by bending a strip of zinc into the desired shape, overlapping the vertical edges, and bending the lower edge thereof inward to form a flange a. A bottom disk a' is set upon this flange and may be soldered thereto for a part of its periphery only, but should be left free at and 70 near the vertical edges of said bent strip. In the best construction this strip is only soldered to the bottom for about one-third its diameter at points as remote as possible from the overlapping edges. Within this cup is 75 placed a package comprising the shell C, made of suitable bibulous material, such as is usually employed to line zinc cups in dry batteries, the centrally-placed carbon element D, and a filling E of the usual battery-filling 80 packed as tightly as practicable. This bibulous lining extends across the bottom of the cup in the form of one or more disks e. A cover-disk K, preferably made of paraffin-pulp board, may also be placed on top of the 85 filling closely embracing the element D, and the top edge of the lining may be lapped over onto this cover-disk. This package is then sealed in a wrapper made of some easily-de-90stroyed insulating material which is impervious to moisture—as, for example, paraffin-paper. The parts of this wrapper may be glued or otherwise sealed together, or the whole package may be immersed in some such substance as paraffin, so as to render any evaporation 95 of the moisture from the inclosed packing substantially impossible. A disk K' may be placed upon the top of the package and glued thereto. This package is to be made in a suitable mold. The zinc cup A, properly contracted in diameter and restrained from expanding during the operation, has been used 100

for this purpose, although possibly a mold capable of being opened completely from top to bottom might better serve the purpose practically. The paraffin-paper employed as the 5 wrapper of this package not only serves to prevent the evaporation of moisture, but it also serves to insulate electrically the package from the cup A. This package, constructed as described, is then placed within cup A: 10 Preferably, however, the cup is lined with some material—as, for example, the lining M m of paper which is not coated with paraffin—for the purpose of keeping the interior surface of the zinc cup from contacting with the par- 15 affin-paper, because if it did contact therewith it might become to a greater or less extent coated with the paraffin and so to that extent be rendered inoperative when the cell is transformed for use.

20 The package having been placed in the zinc cup, this zinc cup is then inserted as far as practicable into another cup G, preferably made of zinc and similar in shape, but a trifle larger in diameter, thereby forming the structure shown in Fig. 1, which is the form in which the cell is to be offered for sale. When in this form, it is absolutely inert and suffers no deterioration so long as it is allowed to remain in this condition. When, however, it 25 is desired to use the cell, the zinc cup A is removed from the cup G, the package is removed from zinc cup A, and the paraffin-paper wrapper is torn from said package. The package is then replaced in the cup A, and this 30 cup is put back into the cup G and pushed into the same as far as possible. This contracts cup A tightly around the package and into intimate contact with the bibulous shell C. The cell may now be used; but it will be 35 rendered very much more efficient if prior to use the battery-filling E is packed down more tightly than it is possible to pack it practically when it is only confined by the bibulous covering and the paraffin-paper wrapper.

40 This filling may be packed by placing a disk—for example, a disk of wood having a hole for the carbon element to pass through—on top of the battery mix and pounding it down. A wood disk J, capable of being used for this purpose, may be placed in the cup G below cup A when the parts are assembled for sale in the 45 form shown in Fig. 1. The cell transformed in the manner described is ready for immediate use. If the battery-filling is packed 50 tightly by pounding upon said disk, the battery will be found to be even more efficient than the dry cells as heretofore constructed, because the battery-filling can be packed in this way more tightly than it is ordinarily 55 packed in the dry cells of commerce.

60 In removing the paraffin-paper wrapper it is only necessary to move the side and bottom portions thereof. The top parts of said wrapper if allowed to remain will serve as a

70 seal for the cell, serving substantially the same function as the pitch seal commonly employed in the ordinary dry cell.

The binding-posts P P' may be permanently secured to the cup A and the carbon electrode D.

Having described my invention, I claim—

1. A new article of manufacture comprising a battery-cell wherein one of the electrodes is separated from the other part of the cell by an insulating-partition which is also impervious to moisture, whereby the cell is rendered inactive until such partition is removed, but becomes active by the mere removal of such partition. 75

2. A battery-cell comprising an outer electrode in the form of a cup, and a package fitted to said cup and sealed in an easily-destructible wrapper of insulating material which is also impervious to moisture, said package so sealed up consisting of an outer shell of 80 bibulous material, an electrode in said shell, and finely-communited battery-filling packed in shell around said electrode. 85

3. A battery-cell comprising an outer zinc cup, and a package fitted therein and sealed in an easily-destructible wrapper of an insulating material which is also impervious to moisture, said package consisting of an outer shell of bibulous material, a carbon electrode 90 centrally placed within said shell, and finely-communited battery-filling packed in said 95 bibulous shell around said carbon electrode.

4. A battery-cell comprising an outer zinc cup of variable diameter, an outer cup into which said zinc cup may be inserted, and a package fitted within said zinc cup and sealed in an easily-destructible wrapper of insulating material which is also impervious to moisture, said package so sealed up consisting of an outer shell of bibulous material, 100 a carbon electrode within said shell, and finely-communited battery-filling packed 105 within said shell around said electrode. 110

5. In a battery-cell comprising a zinc cup of variable diameter, a shell of bibulous material, a carbon electrode, and finely-communited battery-filling packed around said carbon electrode within said shell of bibulous material, a removable insulating-wrapper between said zinc cup and bibulous shell, and 115 means for contracting the diameter of said zinc cup. 120

6. In a battery-cell, a zinc electrode comprising a bottom disk and an upright wall which is formed by bending a strip of zinc into substantially cylindrical form and overlapping its upright edges, said strip being unattached to said disk at and for a considerable distance from said overlapping edges thereof. 125

7. In a battery-cell, a zinc cup comprising a strip bent into substantially cylindrical form with overlapping edges and having its

lower edge bent inward, combined with a disk within said cup resting upon said flange but being unattached to said flange at the overlapping edges of said wall, and for a considerable distance therefrom.

8. A battery-cell comprising an outer zinc cup circular in cross-section but of slightly-increasing diameter from bottom to top, a zinc cup similarly shaped but contractible as to diameter, which cup is fitted to the outer cup and is adapted to be contracted in diameter by being forced down into said outer cup, a protecting-lining to the inner cup, and a package within said inner cup comprising a shell of bibulous material, a carbon electrode therein, finely-communited battery-filling packed within said shell around said electrode, and a wrapper sealed upon said packages and consisting of easily-destructible insulating material which is also impervious to moisture.

9. A battery-cell comprising an outer zinc cup circular in cross-section but of slightly-increasing diameter from bottom to top, a zinc cup similarly shaped but contractible as to diameter, which cup is fitted to the outer cup and is adapted to be contracted in diameter by being forced down into said outer cup, a protecting-lining to the inner cup, and a package within said inner cup comprising a shell of bibulous material, a carbon electrode therein, finely-communited battery-filling packed within said shell around said electrode, and a wrapper of paraffin-paper sealed around said package.

In testimony whereof I hereunto affix my signature in the presence of two witnesses.

JOHN W. BROWN.
